US00D999380S

(12) **United States Design Patent** (10) Patent No.: **US D999,380 S**
(45) Date of Patent: **** Sep. 19, 2023**

(54) **VEIN IMAGER AND CRADLE IN COMBINATION**

- (71) Applicant: **AccuVein Inc.**, Medford, NY (US)
(72) Inventors: **Ron Goldman**, Cold Spring Harbor, NY (US); **Fred Wood**, Medford, NY (US); **Vincent Luciano**, Shoreham, NY (US)
(73) Assignee: **AccuVein, Inc.**, Medford, NY (US)

(**) Term: **15 Years**

(21) Appl. No.: **29/767,192**

(22) Filed: **Jan. 21, 2021**

Related U.S. Application Data

- (63) Continuation of application No. 16/595,750, filed on Oct. 8, 2019, which is a continuation of application No. 15/678,355, filed on Aug. 16, 2017, now Pat. No. 10,518,046, which is a continuation of application No. 14/718,422, filed on May 21, 2015, now Pat. No. 9,789,267, which is a continuation of application No. 13/778,426, filed on Feb. 27, 2013, now Pat. No. 9,061,109, which is a continuation of application No. 12/804,506, filed on Jul. 22, 2010, now Pat. No. 8,463,364.
(60) Provisional application No. 61/271,587, filed on Jul. 22, 2009.

CLAIM

The ornamental design for a vein imager and cradle in combination, as shown and described.

DESCRIPTION

The sole FIGURE is a front view of a vein imager and cradle in combination showing our new design.

The broken lines shown in the drawing depict portions of the vein imager and cradle in combination that form no part of the claimed design.

1 Claim, 1 Drawing Sheet
